FIG. 1

FIG. 2

FIG. 3

FIG. 4

FIG. 5

FIG. 6

FIG. 1 is a perspective view of the self-propelled unmanned tractor embodying my novel design.

FIG. 2 is a side elevational view of the same.

FIG. 3 is a front elevational view of the same.

FIG. 4 is a perspective view of a modified form of tractor embodying my novel design.

FIG. 5 is a plan view of the same.

FIG. 6 is a rear elevational view of the same.

The coupler element shown in broken lines at the rear in FIGURES 2, 3, 5 and 6 is included only for illustrative purposes. The dominant features of my design reside in the portions shown in full lines.

I claim:

The ornamental design for a self-propelled unmanned tractor, as shown and described.
